SURFACE ORNAMENTATION OF WALLS.

No. 16,529.

Patented Feb. 16, 1886.

UNITED STATES PATENT OFFICE.

FREDERICK MANKEY, OF WILLIAMSPORT, PENNSYLVANIA.

DESIGN FOR SURFACE ORNAMENTATION OF WALLS.

SPECIFICATION forming part of Design No. 16,529, dated February 16, 1886.

Application filed November 13, 1885. Serial No. 182,761. Term of patent 7 years.

To all whom it may concern:

Be it known that I, FREDERICK MANKEY, of Williamsport, Lycoming county, Pennsylvania, have invented and produced a new and original Design for Surface Ornamentation of Walls, &c., of which the following is a specification, reference being had to the accompanying photograph, forming part hereof.

Upon the surface appears a configuration of lateral bars or strips, as A and B, the bar A appearing at its edge to overlap the bar B. Upon the edge of bar A is formed a series of scallops, B', each scallop having one side, C, steeper or of greater curvature than the opposite side, D. The scallops of bar A are disposed opposite the scallops of bar B. On the

face of each bar are diagonal channels E. Between said channels may appear circular depressions F.

I claim—

The design for surface ornamentation of walls, &c., substantially as herein shown and described, which consists of the bars A B, the bar A having the appearance of overlapping the bar B, the said bars having along their edges irregular scallops B' and on their faces inclined channels E, alternating with circular depressions F.

FREDERICK MANKEY.
